[57] CLAIM

The ornamental design for grass shears, as shown and described.

DESCRIPTION

FIG. 1 is a front elevational view of grass shears showing our new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a front elevational view thereof wherein the handle position is rotated;

FIGS. 8, 9, 10, 11, 12, 13, 14 and 15 are cross-sectional views along the lines 8—8 through 15—15 of FIG. 1, respectively.
